FOLDER FOR BILLS OR THE LIKE AND
POCKET CONSTRUCTION

Henry M. Herbener, Thomasville, Ga.

Application February 16, 1951, Serial No. 211,309

3 Claims. (Cl. 150—38)

1

My invention relates to folders for receiving and holding bills, cards, photographs or the like and to a pocket construction.

An important object of the invention is to provide a pocket unit provided with a window for displaying a card or the like with means for holding such card against displacement or removal, when the pocket unit is opened for manipulation of the contents thereof.

A further object of the invention is to provide a folder of the above-mentioned character having the pocket unit with the window and having the pocket unit open at one edge of the folder so that the pocket unit may be adjusted to the open position to provide access to the interior of the same without opening the main units of the folder.

A further object of the invention is to provide a folder so constructed that most of the items can be removed without moving the major portion or portions of the folder to the open position.

A further object of the invention is to provide the maximum length for the card receiving pocket having a window, which is rendered possible by eliminating stitching at both ends of the pocket and provides a bellows opening effect for maximum capacity.

A further object of the invention is to provide a folder having all exposed edges turned.

A further object of the invention is to provide a folder of the above-mentioned character which is compact and relatively thin.

Other objects and advantages of the invention will be apparent during the course of the following description.

In the accompanying drawings forming a part of this application and in which like numerals are employed to designate like parts throughout same,

Figure 1 is a plan view of a blank forming the body portion of the folder,

Figure 2 is a similar view of the blank included in the pocket unit,

Figure 3 is a similar view of the blank showing the card holding tongue folded over the inner face of the window side of the blank and stitched thereto,

Figure 4 is a plan view of the body portion forming blank and the pocket unit forming blank, showing the next step in the assembling of the device and the sewing in the flat condition of one side of the pocket unit forming blank to the tongue of the body portion forming blank,

Figure 5 is a plan view of the partly assembled folder showing the pocket forming unit blank arranged over the body portion forming blank,

2

Figure 6 is a similar view, showing the next step in assembling the folder, wherein the window side of the pocket unit forming blank is in the folded position and the sides of the pocket unit forming blank are sewed to the tongue of the side of the body portion forming blank,

Figure 7 is a similar view showing the manner of inserting the transparent sheet or card in place beneath the window side,

Figure 7^a is a transverse section on line 7^a—7^a of Figure 7,

Figure 8 is a plan view of the elements thus far assembled, showing the window side folded laterally so that the transverse tongue may be folded over and sewed to the pocket side and the body portion side,

Figure 9 is a plan view of the folder, inverted with respect to Figure 8, and parts broken away,

Figure 10 is a plan view of the folder having the partition element secured to one body side,

Figure 11 is a similar view, inverted with respect to Figure 10,

Figure 12 is a longitudinal section taken on line 12—12 of Figure 11,

Figure 13 is a central longitudinal section through the completed bill folder in the closed condition,

Figure 14 is a transverse section through the closed bill folder taken on line 14—14 of Figure 13,

Figure 15 is a plan view of the blank included in the pocket unit, partly assembled, and corresponding to Figure 3, showing a modification of the construction,

Figure 16 is a plan view of the bill folder open and viewed from the inner side, showing the modified form of the invention,

Figure 17 is a fragmentary plan view of the bill folder, viewed from the outer side,

Figure 18 is a central vertical longitudinal section through the modified bill folder in the completely closed condition, and,

Figure 19 is a longitudinal section taken on line 19—19 of Figure 17.

In the drawings:

The numeral 15 designates a body portion forming blank, including body portion sides 16 and 17, the side 17 being foldable over side 16 approximately on the line 18. The side 16 is provided at its longitudinal edges with longitudinal tongues 19, foldable upon lines 20, and upon its outer end with a transverse tongue 21, foldable upon the transverse line 22. The side 17 is provided at one longitudinal edge with a longitudinal tongue 23, foldable upon a longitudinal line 24.

55

The numeral 25 designates a pocket unit forming blank, comprising a pocket unit forming side 26, and a window side 27. The window side 27 is folded over the side 26 upon a transverse line 28. The window side 27 has an opening formed therein, to provide a window 29. Carried by the right longitudinal edge of the window side 27, Figure 2, is a wide longitudinal tongue 30, having a considerably greater width than the tongue 19. The tongue 30 is foldable over the window side 27 upon a longitudinal line 31. At its outer or free end, the window side 27 is provided with a transverse flap 32, carrying a resilient socket 33 for receiving a headed stud 34, which is arranged upon the outer face of the side 16 and is suitably secured thereto. This resilient socket and stud form the usual detachable snap fastener. The numeral 35 designates a similar headed stud, arranged upon the outer face of the side 16, and secured thereto, for a purpose to be described. The stud 35 is disposed longitudinally inwardly of the stud 34.

The first step in assembling the pocket unit is to fold the wide tongue 30 inwardly, and this tongue is then secured to the adjacent portion of the window side 27 by a longitudinal line of stitching 36, passing through the tongue 30 and window side 27, Figure 7^a. The line of stitching 36 is close to the folded edge of the tongue 30, and is spaced a considerable distance from the inner edge of the tongue 30, so that this inner edge projects inwardly beyond the line of stitching 36 for a substantial distance. The next step in assembling, Figure 4, is to arrange the blank 15 with its inner face uppermost and flat, and the blank 25 with its inner face and wide tongue 30 lowermost and arrange the pocket unit forming side 26 over the right tongue 19, and while these parts are in the open flat position the side 26 is secured to the tongue 19 by a longitudinal line of stitching 37, passing through the side 26 and tongue 19. The blank 25 is now swung over the blank 15, Figure 5, and side 26 is opposite side 16 and window side 27 is opposite side 17. The tongue 19 to the right, is now above side 26. Tongue 19 to the left, Figure 5, is now folded over the upper face of side 26, Figures 6 and 7^a, and when the side 27 is folded transversely over side 26, the tongue 19 to the left is now positioned between side 26 and window side 27, and these parts are secured together by a longitudinal line of stitching 38, passing through side 26, tongue 19 and window side 27 but not through side 16, Figure 7^a. The side 26 forms with side 16 a pocket 39, and this pocket is now open at its inner and outer ends and the line of stitching 38 may be formed by a tubular work sewing machine having a part inserted through either end of the pocket 39. The transverse tongue 21 is now in the open position and has not been sewed to the sides 26 and 16. The window side 27 may now be folded laterally, Figure 8, and the tongue 21 folded transversely over the side 26, and this tongue is secured in place by a transverse line of stitching 40, passing through the tongue 21, the side 26 and the side 16, Figure 13, thus closing the outer end of the pocket 39.

The numeral 41 designates a partition, having one longitudinal edge secured to the longitudinal tongue 23, Figures 1 and 14 and 10 and 11, by a line of stitching 42. This partition has an inner edge 43, to be arranged near and spaced from the folding line 18. The partition includes a pocket 44, closed at its inner end. The partition carries at its outer end an elongated flap

45, having folded tongues 46 and 47, secured together by a resilient socket 48. The flap 45 and its tongues form a coin receiving pocket to receive the coins from the pocket 44, and the flap 45 is transversely foldable so that its resilient socket 48 will receive the headed stud 35, the socket and stud forming a snap fastener. The flap 45 is much longer than the flap 32 and extends over and completely covers the flap 32 when the resilient socket 48 is held upon the stud 35. Partition 41 and body portion is shown in Pat. No. 2,358,008.

The side 26 forms with the side 16, the pocket 39, as stated and the inner end of this pocket next to the side 17 is open, Figure 12. The window side 27 forms with the side 26 a pocket 49. When the flap 32 is in the open position, a transparent sheet 50 is inserted endwise into the pocket 49, and has one longitudinal edge held in place by the closed longitudinal edge of the pocket while its opposite longitudinal edge engages between a portion of the pocket side 27 and the wide tongue 30, Figure 7^a. This transparent sheet 50 engages the closed end of the pocket, and the outer end of the transparent sheet is held in place by the flap 32 when the flap is secured in the closed position. The transparent sheet 50 is therefore held in place and will cover the window opening 29. When the flap 32 is held in the closed position, the pocket 49 is closed at its inner and outer ends and at its left longitudinal edge, Figure 7^a, while the pocket is open throughout its entire length at its right longitudinal edge. By longitudinally flexing the pocket unit, the pocket will be further opened at its right longitudinal edge, so that access may be readily had to the interior of the pocket 49. An element 51 is inserted within the pocket 49, immediately behind the transparent sheet 50 in engagement therewith and is held in place by the same means that holds the sheet 50 in place. The element 51 may be a driver's permit, a card, photograph or the like.

When the flap 32 is held in the closed position, the partition 41 may be folded over the side 17, and the folding edge 43 will be arranged near the folding line 18, and the flap 45 will extend beyond the side 17 for a considerable distance. The bills may now be laid upon the side 17 and window side 27, with the upper portion of the bills beneath the partition 41. The side 17 is now folded transversely over the side 27, and the flap 45 is folded over the inner open end of the pocket 44 and over the flap 32, and has its resilient socket 48 secured to the stud 35. With the several parts of the bill folder thus held in the closed position, the bill folder may be longitudinally compressed and this will automatically open further the pocket 49 at its right longitudinal edge, Figure 4, so that papers or the like may be removed from this pocket without opening the major portions of the bill folder. By bending back the free corner of the side 17, the bills may be stripped from the folder without opening the major portions of the folder. When the flap 45 is released from connection with the side 16, the partition 41 and window side 27 may be swung to the open flat position, as shown in dotted lines, Figure 10, whereby the card 51 or the like may be readily observed through the window opening 29.

In Figures 15 to 18 I have shown a modified form of bill folder. As more clearly shown in Figure 15, the longitudinal tongue 30 is stitched at 36. This tongue 30 may be folded back to position elements 50 and 51 behind the longitudinal tongue, which will spring back into place when released for holding such elements in place. The

window side 27 is provided at its outer end with a flap 32'. The flap 32' corresponds to the flap 32, Figure 7, but is longer than the flap 32 and is of substantially the same length as the flap 45. The flap 32' has an opening 32a formed therein near its free end, this opening receives the body portion 35' of the stud element 35 and the flap 32' is held beneath the outer flange 36'. It is thus seen that the flap 32' is permanently held in the closed position by the stud element 35. In this construction, the stud element 34, Figure 1, is omitted. The flap 32' covers the outer open end of the pocket 49 and the pocket therefore has a maximum all over length. This tongue 32' also covers the outer open end of the pocket 39, the transverse tongue 21 and stitching 40, Figure 13, being omitted, and the pocket 39 therefore has the all over maximum length. The pocket forming blank 25 is assembled upon the body portion side 16 in a similar manner as described in connection with the first form of the invention. The main flap 45 which may be slightly longer than the flap 32' is folded over the flap 32' when the bill folder is closed, and its resilient socket 48 is applied to the stud 35, the stud 35 and socket 48 constituting a conventional snap fastener. All other parts of the bill folder remain identical with those shown and described in connection with the first form of the invention.

In connection with the modification of the bill folder, Figures 15 to 18 inclusive, the pocket 49 is open at its longitudinal edge adjacent to the tongue 30. The elements 50 and 51 are inserted through this longitudinal open edge and positioned behind the longitudinal tongue 30, which may be folded back for this purpose. Other papers or the like may be inserted within and removed from the pocket through the longitudinal edge opening, as previously explained.

I also contemplate closing the outer end of the pocket 49 by a line of stitching connecting the adjacent sides, and omitting the flap 32', but this would shorten the length of the pocket 49. Further, the flap 32' produces a rounded edge at one end of the folder. The modified form of the invention dispenses with one snap fastener, and the remaining snap fastener is common to both flaps.

It is to be understood that the forms of my invention are to be taken as preferred examples of the same and that various changes in the shape, size and arrangement of parts may be resorted to without departing from the spirit of my invention or the scope of the subjoined claims.

Having thus described my invention, I claim:

1. A billfolder comprising a body portion including connected first and second sides, one side being foldable transversely over the other side, a partition carried by the first body portion side and foldable longitudinally over such side, the partition having an inner billfolding edge arranged near the line of folding of the first and second sides, a separate blank transversely folded for providing a first pocket side and a second pocket side and a first folded transverse edge, the first pocket side being arranged next to the second body side and the second pocket side next to the first pocket side, a line of stitching disposed adjacent to one side edge of the second body portion side and secured to such second body portion side and passing through the first pocket side and the second pocket side, a second line of stitching arranged adjacent to the opposite side edge of the second

body portion side and secured to such body portion side and passing through the first pocket side and not through the second pocket side, the arrangement providing a permanent opening at one side edge of the second pocket side, a flap secured to the outer end of the second pocket side and foldable transversely over the second body portion side and forming a second folded transverse edge and secured to the body portion side, and a second flap carried by the partition and foldable transversely over the second body portion side and detachably secured to the second body portion side, the first pocket side forming with the second body portion side a first pocket having its inner end open and a second pocket side forming with the first pocket side a second pocket having its inner end covered by the first folded transverse edge and its outer end open, the outer open end of the second pocket being covered by the second folded transverse edge of the first flap.

2. A billfolder comprising a body portion including connected first and second sides, one side being foldable transversely over the other side, a partition carried by the first body portion side and foldable longitudinally over such side, the partition having an inner billfolding edge arranged near the line of folding of the first and second sides, a separate blank transversely folded for providing a first pocket side and a second pocket side and a first folded transverse edge, the first pocket side being arranged next to the second body side and the second pocket side next to the first pocket side, a line of stitching disposed adjacent to one side edge of the second body portion side and secured to such second body portion side and passing through the first pocket side and the second pocket side, a second line of stitching arranged adjacent to the opposite side edge of the second body portion side and secured to such body portion side and passing through the first pocket side and not through the second pocket side, the arrangement providing a permanent opening at one side edge of the second pocket side, a flap secured to the outer end of the second pocket side and foldable transversely over the second body portion side and forming a second folded transverse edge and secured to the second body portion side, and a second flap carried by the partition and foldable transversely over the second body portion side and detachably secured to the second body portion side, the first pocket side forming with the second body portion side a first pocket having its inner and outer ends open and the second pocket side forming with the first pocket side a second pocket having its inner end covered by the first folded transverse edge and its outer end open, the outer open ends of the first and second pockets being covered by the second folded transverse edge of the first flap.

3. A billfolder comprising a body portion including connected first and second sides, one side being folded transversely over the other side, a partition carried by the first body portion side and foldable longitudinally over such side, the partition having an inner billfolding edge arranged near the line of folding of the first and second sides, a separate blank transversely folded for providing a first pocket side and a second pocket side and a first folded transverse edge, the first pocket side being arranged next to the second body side and the second pocket side next to the first pocket side, a line of stitching disposed adjacent to one side edge of the second body portion side and secured to such second body portion side and passing through the first pocket side and the second pocket side, a second line of stitching disposed adjacent to the opposite side edge of the second

portion side and secured to such second body portion side and passing through the first pocket side and the second pocket side, a second line of stitching arranged adjacent to the opposite side edge of the second body portion side and secured to such second body portion side and passing through the first pocket side and not through the second pocket side, the arrangement providing a permanent opening at one side edge of the second pocket side, a flap secured to the outer end of the second pocket side and foldable transversely over the second body portion side and forming a second folded transverse edge, a second flap carried by the partition and foldable transversely over the second body portion side, a stud secured to the second body portion side and permanently connecting the first flap with the second body portion side, and a socket secured to the second flap and arranged for detachable engagement with said stud, the first 20 pocket side forming with the second body portion side a first pocket having its inner and outer ends open and the second pocket side forming

with the first pocket side a second pocket having its inner end covered by the first folded transverse edge and its outer end open, the outer open ends of the first and second pockets being covered by the second folded transverse edge of the first flap.

HENRY M. HERBENER.
